KEY FOR ROLLING COLLAPSIBLE TUBES

Herbert W. Bubar, Toronto, Ontario, Canada

Application June 22, 1949, Serial No. 100,565

3 Claims. (Cl. 222—99)

1

This invention relates to a winding key for rolling the empty portion of a collapsible tube.

Winding keys for this type of a tube having co-acting tube engaging arms and a handle for rotating said arms to wind the empty portion of a collapsible tube therearound have been known and used in the past. Their constructions, however, in respect of the manner in which the tube engaging arms are brought and retained together to grip the empty portion of the tube, have been quite inconvenient to use and expensive to manufacture. My invention overcomes the difficulties of this nature in use and manufacture of the tube rolling keys of the prior art.

A tube rolling key of the type under discussion has two co-acting tube engaging arms. According to my invention, each of these arms has a handle bar extending therefrom adjacent its free end. The bars are each formed with a roughened surface for sliding engagement one with the other, as the co-acting arms are brought together to grip the empty portion of a tube, and the arms are resilient whereby to urge the said roughened surfaces into engagement with each other to retain the arms from separating after they have been actuated together. The invention will be clearly understood after reference to the following detailed specification read in conjunction with the drawings.

In the drawings:

Figure 1 is a perspective view showing the manner in which a tube winding key according to the present invention is used.

Figure 2 is a perspective view showing a single piece of wire bent so that it can be made to form a tube key according to the invention.

Figure 3 is a view of the tube winder of Figure 2 ready for use.

Figure 4 is a view showing the handle bars displaced from each other and a manner of forming the roughened surfaces thereon according to the preferred embodiment of the invention.

Referring to the drawings, the letter A generally indicates a key for winding collapsible tubes according to the invention. The embodiment shown is formed from a single piece of wire bent into a U-shape, the sides of the U forming two co-acting tube engaging arms 10 and 11 each having its free end formed into a minor U with an elongated side arm to provide handle bars 12 and 13. The handle bars 12 and 13 are each formed with roughened surfaces 14 and 15 respectively for sliding inter-engagement as the co-acting arms 10 and 11 are actuated towards each other.

2

When the wire is first formed to the shape just described it is sprung as illustrated in Figure 2 to cause the handle bars 12 and 13 to normally assume a position displaced from each other so that when the roughened surface 14 of the handle bar 12 is caused to overlie the roughened surface 15 of the handle bar 13 as in Figure 3, there will be a resilient force, urging the roughened surfaces 14 and 15 into engagement with each other. It will be apparent as the arms 10 and 11 are actuated towards each other from a position shown in Figure 3 that the roughened surfaces 14 and 15 will slidably engage with each other. Once the arms 10 and 11 have been brought together, however, their resiliency will cause the roughened surfaces 14 and 15 of the bars 12 and 13 to lock together and prevent them from separating.

The form of the roughened surface for the bars 12 and 13 is illustrated in the drawings. The surfaces there shown will be seen to comprise a series of teeth 16 each having a flank 17 substantially perpendicular to the bar and flank 18 inclined to the bar and designed such that the inclined flanks slidably engage with each other as the arms 10 and 11 are brought together and the straight flanks lock with each other due to the resiliency of the arms 10 and 11 to prevent bars 12 and 13 from moving with respect to each other in the opposite direction.

30 The manner of using the key is illustrated in Figure 1. The empty bottom portion of the tube is inserted between the arms 10 and 11. Pressure is then exerted at the end of the handle bars 12 and 13 to cause the arms 10 and 11 to engage with opposite sides of the tube. Once this engagement has been effected, the roughened surfaces 14 and 15 and the resiliency of the arms 10 and 11 will prevent the arms from becoming separated again. It is then merely necessary to turn the handle of the key and roll the empty portion of the tube thereon.

If it is desired to separate the co-acting arms 10 and 11 after they have been actuated together it is merely necessary to separate the locked roughened surfaces 14 and 15 as shown in Figure 4. This will free the arms to spread apart again.

What I claim as my invention is:

50 1. A key for winding collapsible tubes comprising two co-acting tube engaging arms each having a handle bar extending therefrom adjacent its free end, each of said bars being formed with a roughened surface for sliding engagement with the other as the co-acting arms are actuated towards each other, said arms being resilient to urge said roughened surfaces into engagement

with each other, said roughened surfaces being formed to slidably engage with each other as the arms are actuated towards each other and to lock with each other to prevent the arms from being actuated in the opposite direction.

2. A key for winding collapsible tubes comprising two co-acting tube engaging arms each having a handle bar extending therefrom adjacent its free end, each of said bars being formed with a roughened surface for sliding engagement with the other as the co-acting arms are actuated towards each other, said arms being resilient to urge said roughened surfaces into engagement with each other, said roughened surfaces on said bar comprising a series of teeth, each tooth having a flank substantially perpendicular to said bar and a flank inclined to said bar, the inclined flanks on the one bar being designed to slidably engage with the inclined flanks on the other bar when said arms are actuated towards each other 20 as aforesaid, perpendicular flanks on one bar locking with perpendicular flanks on the other bar to prevent relative movement therebetween in the opposite direction.

3. A key for winding collapsible tubes comprising a single piece of wire bent into a U-shape, the sides of said U forming two co-acting tube engaging arms, the free ends of said arms having their ends bent into a minor U to form handle bars, each of said bars being formed with a 30 roughened surface, said arms being resilient to

urge said roughened surfaces into engagement with each other, said roughened surfaces being formed for sliding engagement to slidably engage with each other as the arms are actuated towards each other and to lock with each other to prevent the arms from moving in the opposite direction, said roughened surfaces on said bars comprising a series of teeth, each tooth having a flank substantially perpendicular to said bar and a flank inclined to said bar, the inclined flanks on the one bar being designed to slidably engage with the inclined flanks on the other bar when said arms are actuated towards each other as aforesaid, the perpendicular flanks on one bar locking 15 with the perpendicular flanks on the other bar to prevent relative movement therebetween in the opposite direction.
